UNITED STATES PATENT OFFICE.

MAX WEST POWELL, OF CHICAGO, ILLINOIS.

HOISTING MECHANISM.

Application filed July 30, 1924. Serial No. 723,043.

To all whom it may concern:

Be it known that I, MAX WEST POWELL, a citizen of the United States, and a resident of the city of Chicago, in the county of Cook and State of Illinois, have invented certain new and useful Improvements in a Hoisting Mechanism; and I hereby declare that the following is a full, clear, and exact description of the same, reference being had to the accompanying drawings, and to the numerals of reference marked thereon, which form a part of this specification.

This invention relates to improvements in hoisting mechanisms, and particularly to improvements in automatic locking devices for the same and to controlling mechanism for the hoisting apparatus.

One object of the invention is to provide an automatic lock for a hoisting mechanism which will always be ready instantly to lock the mechanism in case of damage or breakage so as to prevent the accidental lowering of the load.

Another object is to provide a lock which will automatically come into operation whenever the driven member is released from the driving mechanism when it commences to run away.

Other and further important objects of this invention will be apparent from the disclosures in the accompanying drawings and the following specification.

The invention (in a preferred form) is illustrated on the drawings and hereinafter more fully described.

On the drawings:

Figure 1 is a plan view of the hoisting mechanism with parts broken away.

Figure 2 is a section on the line 2—2 of Figure 1.

Figure 3 is a section on the line 3—3 of Figure 2.

Figure 4 is a section on the line 4—4 of Figure 1.

Figure 5 is a section on the line 5—5 of Figure 4.

Figure 6 is a detail view of the operating lever.

Figure 7 is a section on the line 7—7 of Figure 4.

Figure 8 is a section on the line 8—8 of Figure 2.

Figure 9 is a side elevation of the hoisting mechanism.

As shown on the drawings:

The hoist comprises side frames 10 in

which are journaled a driving shaft 11 and a drum supporting shaft 12. Rotatably mounted on the shaft 11 are pinions 13 and 14. Parallel to the shaft 11 is a jack shaft 15 on which pinions 16 and 17 are non-rotatably mounted. The pinions 13 and 16 mesh together while the pinions 14 and 17 being smaller may revolve independently of each other. Above the jack-shaft 15 is another jack-shaft 18 which carries at one end a gear wheel 19 in mesh with both pinions 14 and 17. Consequently if pinion 13 is coupled to the shaft 11 the shaft 18 is rotated through pinions 16, shaft 15, pinion 17 and gear wheel 19. If pinion 14 is coupled to the shaft 11 the shaft 18 is rotated in the reverse direction by direct engagement with the gear wheel 19. As the jack-shaft 18 carries a pinion 20 in mesh with a gear wheel 21 connected to the drum 22, the latter may be rotated in either direction without reversing the direction of rotation of the shaft 11.

Clutches 23 and 24 serve to connect the pinions 13 and 14 to the shaft 11. A sliding sleeve 25 brings the clutches into operation alternatively. This sliding sleeve is operated by means of a bell-crank 26 pivotally mounted on a pin 27, having one arm forked and slotted for engagement with pins 28 on the sleeve 25 while the other arm passes through an aperture in a lever 29. This lever, pivotally mounted on the frame 10 by a pin 30, controls the operation of the hoist.

In addition to manual control of this lever automatic control is also provided. For this purpose a second bell-crank 31 is provided also pivoted on the pin 27. One end of this bell-crank passes through a slot 32 in the lever 29 while the other arm extends over a tripping mechanism.

This tripping mechanism comprises a sleeve 33 splined at one end upon a sleeve 34 rotatably mounted on a fixed shaft 35 and engaging at the other end a threaded portion 36 of the shaft 35. Consequently if the sleeve 34 is rotated the sleeve 33 moves axially in one direction or the other depending upon the direction of rotation of the sleeve 34. The sleeve 33 carries cams 37 at each end for engagement with the end of the bell-crank 31. The sleeve 34 is rotated from the drum shaft 12 by means of sprocket 38, chain 39 and sprocket 40.

While the bell-crank 31 engages the same

lever that operates the clutch bell-crank 26 the movement of the bell-crank 31 by the cams 37 throws one clutch out of engagement, it does not directly bring the other 5 clutch into operation. It does, however, bring into play the mechanism which accomplishes that result.

This mechanism comprises a shaft 41 parallel to the side frames 10 and rotatably supported thereby. This shaft carries a mutilated worm wheel 42 adapted to engage a worm 43 on the end of the driving shaft 11. Normally this shaft is held with the cutaway part of the worm wheel 42 opposite the worm by means of a cam 44 on the shaft 41. This cam is provided with a shoulder 45 arranged to engage the projecting end of the bell-crank 31 and prevent the shaft 41 rotating. The shaft 41 is so counterweighted by a counter weight 41^a that if the end of the bell-crank is moved out of the path of the shoulder 45, the shaft 41 turns to bring its mutilated gear wheel 42 into engagement with the worm 43. Further rotation of the shaft 41 by gear 42 and worm 43 brings the roller 46 on the end of bell-crank 31 into engagement with one side or other of the enlarged part 47 of the cam 44 depending upon the direction the bell-crank has been moved by the cams 37.

This cam portion 47 completes the movement of the bell-crank 31 necessary to operate the lever 29 and thereby move the bell-crank 26 to bring the other clutch into engagement.

In order to hold the bell-crank 31 in engagement with the shoulder 45 until the automatic clutch operating mechanism comes into play, the bell-crank is apertured for the passage of a bolt 48 having springs 49 thereon arranged one on each side of the bell-crank. These springs bear against washers 50 adapted to engage the frame of the hoist as well as the bell-crank, as shown 45 in Figure 7, so that the latter is yieldingly held in neutral position.

In addition to providing both manual and automatic means for operating the clutches, the hoist is also constructed so that the 50 mechanism will always be ready instantly to lock the mechanism in case of damage or breakage so as to prevent the accidental lowering of the load. This lock also automatically comes into operation whenever the 55 drum is released from the driving shaft and the drum commences to run away.

This locking mechanism comprises a toothed wheel 51 bolted to one end of the drum 22 and provided with a peripheral 60 shoulder or rim 52. Upon this shoulder rides a shoe 53, as shown in Figure 3, loosely pivotally connected at 54 to a lever 55 rotatably mounted on a shaft 56. This lever is provided with two laterally extending arms 57 within which are slidably mounted dogs

58. As the drum rotates in the direction of the arrow, Figure 3, the friction between the shoe 53 and the shoulder 52 tends to carry the shoe around with the drum. This movement swings the lever 55 to the left 70 and thereby simultaneously lifts the right hand dog into engagement with one of the teeth on the wheel 51 and locks it against further rotation in that direction. If the drum were rotating in the opposite direction 75 the left-hand dog would be brought into operation. The shock of the blow of the teeth of the wheel 51 upon the dogs 58 is preferably cushioned in any convenient way, such as by inserting rubber blocks 59 in the bottom of the apertures in the arms 57 which receive the dogs 58. The latter may be prevented from turning in the arms 57 by pins 60 which move in slots in the arms.

Such an arrangement as above described 80 would prevent all operation of the hoist and hence means are provided for preventing the operation of the lock except when the drum commences to turn in a direction opposite to that intended. For this purpose a quadrant member 61 attached to the shaft 56 is adapted to engage shoulders 62 on the arms 57 and so restrict the range of movement of the latter. With the member 61 in the position shown in Figure 3 the right 85 hand dog 58 cannot engage the teeth of the wheel 51 but should the direction of rotation reverse the left-hand dog 58 is free to move into engagement with the wheel 51.

The angular position of the shaft 56 and thereby that of the member 61 is controlled by means of a plate 63 having one end pivotally connected at 64 to an arm 65 secured to the shaft 56. The other end of the plate is arranged to overlap the lever 29 and is 100 formed with slots 66 and 67 (Figure 5) for the passage of the ends of the bell-cranks 26 and 31 respectively. The slot 66 is of such length that the lever 29 may move the bell crank 26 from either clutch engaging position 105 to neutral without moving the plate 63. Should, however, the lever be moved further to bring the other clutch into engagement, the plate 63 will be moved and thereby turn the shaft 56 and member 61 so as to allow the drum to rotate in the desired direction while leaving the locking device free to operate whenever the drum turns in the opposite direction.

The slot 67 is longer than the slot 66 so that the plate 63 may be moved by the bell-crank 26 from one clutch-engaging position to the other without moving the bell-crank 31. The slot has recesses along its upper side at each end to enable the bell-crank 31 115 releasably to hold the plate 63 in one or other clutch engaging positions.

The bell-crank 26 is connected to the lever 29 so that the latter cannot move without operating the bell-crank. This is not the 120

case with the other bell-crank 31 the end of which extends through a slot 32 in the lever long enough to allow the latter to move not only into neutral but also into either 5 clutch engaging position without operating the bell-crank 31. In other words the bell-crank 31 may operate the lever 29 but the lever cannot operate the bell crank.

Although the dogs 58 are cushioned the 10 shock of stopping the drum is very great so that the teeth and other parts of the wheel 51 are apt to break. For this reason the wheel 51 is not made integral with the drum so that in the event of breakage the 15 wheel only need be replaced.

Similarly the gear 21 on the drum shaft is made separate from the drum to allow ready replacement in case of breakage of teeth, etc. This gear is operatively connected to the drum 22 and the toothed wheel 51 by means of a rod 70 adapted to slide in an aperture in the wheel 51 and enter an aperture in the gear 22. The end of the screw is threaded in the drum. The 25 axial position of this rod may be adjusted by means of a handwheel 71. When the rod 70 is disengaged the machine may be used as a source of power for driving car puller or the like.

For the same reason the bearings which support the shaft 56 are made separable from the frame. The center bearing 68 is also constructed so that its two halves are pressed towards the shaft 56 by springs 69 to exert a braking action upon the shaft which aids in holding the quadrant member 61 in adjusted position.

I am aware that many changes may be made, and numerous details of construction 40 may be varied through a wide range without departing from the principles of this invention, and I therefore do not purpose limiting the patent granted hereon, otherwise than necessitated by the prior art.

I claim as my invention:

1. A hoist including in combination a drum, a shaft carrying said drum, double clutch operated reversible gear for driving said drum, an arm operating said clutches, a toothed wheel detachably secured to said drum, a rocker shaft, safety locking mechanism on said rocker shaft adapted to co-operate with said toothed wheel, a crank arm on said rocker shaft and a link pivoted 50 to the crank arm having slot connection with said clutch operating arm, the length of such slot being sufficient to allow the clutch arm to move into neutral without moving the link while insufficient to allow the clutch arm to move from one clutch engaging position to the other without moving said link.

2. A hoist including in combination a 65 frame, a shaft journaled in said frame, a drum mounted on said shaft, double clutch

operated reversible gear for driving said drum, an arm operating said clutches, a toothed wheel connected to said drum, a rocker shaft, safety locking mechanism on said rocker shaft adapted to co-operate with 70 said toothed wheel, bearings for said rocker shaft detachably connected to said frame, a crank arm on said rocker shaft and a link connection between said crank arm and said clutch operating arm adapted to operate the 75 safety locking mechanism as the clutch operating arm moves from one clutch engaging position to the other.

3. A hoist including in combination a drum, a shaft carrying said drum, double clutch operated reversible gear for driving said drum, an arm operating said clutches, a toothed wheel detachably secured to said drum, a rocker shaft, a pair of oppositely extending dogs rotatably mounted on 80 said rocker shaft adapted to engage alternatively with said toothed wheel, friction means co-operating with said toothed wheel adapted to throw one or other of said dogs into engagement, and means on said rocker shaft for withholding the operation of said friction means while the drum is rotating 85 in the desired direction.

4. A hoist including in combination a drum, a shaft carrying said drum, double clutch operated reversible gear for driving said drum, an arm operating said clutches, a toothed wheel detachably secured to said drum, a rocker shaft, a pair of oppositely extending dogs rotatably mounted on said 100 rocker shaft adapted to engage alternatively with said toothed wheel, friction means co-operating with said toothed wheel adapted to throw one or other of said dogs into engagement, and means on said rocker shaft 105 for withholding the operation of said friction means while the drum is rotating in the desired direction, said withholding means being operated by movement of the clutch operating arm.

5. A hoist including in combination a drum, a shaft carrying said drum, double clutch operated reversible gear for driving said drum, an arm operating said clutches, a toothed wheel detachably secured to said drum, a rocker shaft, a pair of oppositely extending dogs rotatably mounted on said rocker shaft adapted to engage alternatively with said toothed wheel, friction means co-operating with said toothed wheel adapted to throw one or other of said dogs into engagement, a stop member secured to said rocker shaft adapted in one angular position to prevent one of said dogs engaging said wheel and in another position the other of said dogs, and a crank arm on said rocker shaft for turning the latter.

6. A hoist including in combination a drum, a shaft carrying said drum, double clutch operated reversible gear for driving 130

2

said drum, an arm operating said clutches, a toothed wheel detachably secured to said drum, a rocker shaft, a pair of oppositely extending dogs rotatably mounted on said 5 rocker shaft adapted to engage alternatively with said toothed wheel, friction means cooperating with said toothed wheel adapted to throw one or other of said dogs into engagement, a stop member secured to said 10 rocker shaft adapted in one angular position to prevent one of said dogs engaging said wheel and in another position the other of said dogs, a crank arm on said rocker shaft for turning the latter, and a link 15 pivoted to the crank arm having slot connection with said clutch operating arm, the length of such slot being sufficient to allow the clutch arm to move into neutral without moving the link while insufficient to allow 20 the clutch arm to move from one clutch engaging position to the other without moving said link.

7. A hoist including a frame, a shaft journaled in said frame, a drum mounted on 25 said shaft, double clutch operated reversible gearing for driving said drum, an arm for operating said clutches, a toothed wheel connected to said drum, a rocker shaft, safety dogs loosely mounted on said shaft for co- 30 operation with said toothed wheel, bearings for said rocker detachably connected to said frame, a crank on said rocker shaft and a connection between said arm and crank adapted for throwing said dogs to neutral 35 position at the limits of movement of said crank.

8. A hoist including a drum, a shaft carrying said drum, double clutch operated gearing for driving said drum, an arm for operating said clutches, a toothed wheel 40 detachably secured to said drum, a rocker shaft, a pair of oppositely extending dogs rotatably mounted on said rocker shaft adapted to alternately engage said toothed wheel, friction means cooperating with said 45 toothed wheel adapted to throw one or the other of said dogs into engagement with said toothed wheel, and means on said rocker shaft for withholding the operation of said friction means while the drum is rotating 50 in the desired direction, said means operating during reversal of said clutches.

9. In a hoist including a drum, a locking wheel detachably secured to said drum, a rocker shaft, dogs rotatably mounted on said 55 rocker shaft for engaging said locking wheel, means including shiftable clutches for rotating said drum in either direction, an arm for shifting said clutches, a lever connected with said arm, a connection between said lever and rocker shaft and a device secured to said rocker shaft adapted for shifting said dogs to neutral at the limits of movement of said connection.

In testimony whereof I have hereunto 60 subscribed my name in the presence of two subscribing witnesses.

MAX WEST POWELL.
